[57] CLAIM

The ornamental design for a wind powered bicycle reflector, as shown.

DESCRIPTION

FIG. 1 is a front elevational view of a wind powered bicycle reflector showing my new design;

FIG. 2 is a rear elevational view;

FIG. 3 is a cross-sectional view taken on the lines 3—3 in FIG. 2; and,

FIG. 4 is a typical side elevational view, with other side elevation views being substantially identical owing to the radial symmetry of the design.
